UNITED STATES PATENT OFFICE.

REGNAR KIDDE, OF NEW YORK, N. Y.

SAFETY-HEATER.

1,235,573.

Specification of Letters Patent.

Patented Aug. 7, 1917.

Application filed March 28, 1916. Serial No. 87,226.

To all whom it may concern:

Be it known that I, REGNAR KIDDE, a citizen of the United States, residing at New York city, borough of Manhattan, county 5 and State of New York, have invented certain new and useful Improvements in Safety-Heaters, the following being a full, clear, and exact disclosure of the one form of my invention which I at present deem 10 preferable.

For a detailed description of the present form of my invention, reference may be had to the following specification and to the accompanying drawings, which illustrate my 15 invention, wherein—

Figure 1 is a vertical central section of my heater;

Fig. 2 a horizontal section thereof on the line 2—2 of Fig. 1, the gas burner and its 20 adjuncts being removed;

Fig. 3 is a front elevation thereof;

Fig. 4 is a vertical section on the line 4—4 of Fig. 1;

Figs. 5 and 6 illustrate the inside door.

25 My invention relates to a gas stove or heater suitable for use in garages, or in other situations where the flame has to be guarded from contact with inflammable elements in the atmosphere.

30 Referring to the drawing, A represents an outer casing formed of sheet metal and closed except on the top which is perforated and on the bottom which is open. The casing is mounted on standards K, K, screwed 35 into its bottom and is provided in front with a vertically sliding door B having a handle b. This door is of the full width of the casing and nearly the full height thereof, and slides in vertical grooves at its opposite 40 edges. The compartment formed by the outside casing-walls A may be referred to as the primary chamber. In this primary chamber is formed a secondary chamber by means of the sheet iron walls C spaced a distance away 45 from the aforesaid walls A. The secondary casing is closed on all sides except at the rear where it is provided with an elliptical opening closed by a wire-gauze panel c which puts the secondary chamber in communication with the space between the rear 50 walls A and C, which space is shut off from the primary chamber by the partition E at the top and by the partition E' at the bottom and which is also in communication 55 with a flue or opening a for the outflow of the products of combustion. The partition

E' may be provided with a small opening adjustable in size by a damper, if so desired.

Inside of the secondary chamber is formed a third or tertiary chamber by means of the 60 walls D co-operating with one of the walls C. This third chamber is of the full width of the secondary chamber and is open at the top and bottom, the bottom opening being covered by a gauze panel d. In this third chamber is a gas-burner F with its igniting or pilot burner f, both burners being controlled by interlocking valves f². In that wall C forming the front wall of the third chamber is the door G which is of the construction 70 shown in detail in Figs. 5 and 6. Referring to those figures, the circular door-frame G' is made of a gradually increasing thickness from top to bottom to form an inclined front bearing face on which is seated the circular 75 door. The door is formed of a circular frame G² inclosing a gauze panel G³ and having on its inner face a groove containing a packing ring G⁹ that seats against a circular ridge or flange on the outer face of the 80 frame G¹. The door is hinged at its upper side on the pintle G⁶ and is also provided with a closing spring G⁷. The door, being hinged at the top, tends to close by gravity, the closing tendency being aided by the 85 spring G⁷. In addition, the inclined bearing surface insures that the door will lie in contact therewith under the closing forces just mentioned. To adequately lock the door, I provide a locking-lever G⁴, pivoted to the 90 lower part of frame G', and adapted, when lifted into its upright position, to engage the lug g² on the door and thereby force the door hard down on its seat. A loop G⁵ is then brought down over the upper end of the 95 lever to hold it in place with a wedging action. A screw G⁸ may also be provided in the cross bar of the loop to take up wear. When the loop is lifted the lever can be 100 turned into the position shown in dotted lines to release the door, being arrested in that position by engagement with the stop g³ on the wall C. In that position the lever will project into the downward path of the vertically sliding door B and prevent its closure, while, unless the door B is lifted up, the lever can not come into its said releasing position. That tends to insure the closing of the inside door. The arrangement just described has been devised by me to 105 meet the requirements of the fire department of New York city and, together with

the heater described herein, has been approved and authorized by that department.

In operation the air entering the bottom of the primary chamber passes through the 5 gauze panel *d* beneath the burner *F* into the third chamber where it is heated and passes thence upward into the secondary chamber where it imparts its heat to the walls of that chamber. Thence it goes through the gauze 10 panel *c* into the space between the walls *A* and *C* finally escaping by the flue or opening *a* into the apartment to be heated or into a chimney. The air also passes up into the primary chamber along the heated walls *C* 15 of the secondary chamber and thence escapes into the apartment to be heated through the perforated top wall of the said primary chamber. At no point does the atmosphere of the apartment come into contact with the 20 flame without the intervention of the gauze screen. So long as the pilot flame continues to burn, there is no occasion for opening up the third chamber containing the burner, and the inside door leading to that 25 chamber is adequately secured by the construction I have described.

What I claim as new and desire to secure by Letters Patent is:

1. A heater containing a primary chamber open to the apartment to be heated, a secondary chamber having its walls contained within but separated from the walls of said primary chamber, one wall of said 30 secondary chamber having an opening communicating with the primary chamber and covered with wire gauze, a third chamber contained in said secondary chamber but in communication therewith, a burner in said third chamber, and a space or flue connecting said secondary chamber with the outlet flue or opening for the products of combustion, but cut-off by wire gauze from free communication with said secondary chamber. 35

40 2. A heater containing a primary chamber open at opposite points to the apartment to be heated and a secondary chamber contained in but having its walls spaced from the walls of the said primary chamber and 45 shut off from free communication therewith, a flame burner for heating said secondary chamber, a door for said primary chamber, and a gauze door in one wall of said second- 50

ary chamber adjacent to and in line with the aforesaid door in the primary chamber. 55

3. A heater containing a primary chamber open on opposite sides to the apartment to be heated and a secondary chamber contained in but having its walls spaced from the walls of the primary chamber, a 60 flame burner within said secondary chamber, a door for said primary chamber and an adjacent door in one wall of the secondary chamber arranged to interfere when open with the travel of the door of the primary chamber, and locking means for the door of the secondary chamber to its closed position. 65

4. A heater comprising primary and secondary chambers, the latter included 70 within the former and containing a flame burner and a gauze door for the secondary chamber adapted to close by gravity on an inclined seat and an external lever provided with a latch and adapted to press the door 75 upon its seat when closed.

5. A heater comprising primary and secondary chambers, the latter being included within the former and containing a flame burner, a door in the primary chamber, an adjacent gauze door in the secondary chamber and a retaining device for the said gauze door adapted when in its releasing position to prevent the closure of the said door in the primary chamber. 80

6. A heater comprising primary and secondary chambers, the latter being included within the former and provided with a flame device, and a gauze door for the secondary chamber provided with an external 85 cam lever adapted to retain said door in its closed position by pressure and a retaining latch for said lever.

7. A heater containing primary and secondary chambers, the latter being contained in the former but out of free communication therewith, an internal flame burner for heating the secondary chamber and a gauze door for the secondary chamber having an inclined bearing face and retaining devices for holding the door under pressure in engagement with its said bearing face. 95

In witness whereof I have hereunto set my hand this 21st day of March, 1916.

REGNAR KIDDE.
